SCREW THREAD COMPARATOR

Bror W. Swanson, Elmwood, Conn., assignor, by
mesne assignments, to Anthony F. Kasprow,
Felix A. Kasprow, Joseph W. Kasprow, Stephen
G. Kasprow, New Britain, Conn., and
Meyer E. Bailey, New Haven, Conn.

Application February 16, 1945, Serial No. 578,323

8 Claims. (Cl. 33—199)

1

My invention relates to the class of devices that are employed for determining the condition of screw threads as to form, and an object of the invention, among others, is the provision of a device of this sort that is simple in construction and particularly accurate in the functions performed by it.

One form of a device embodying the invention and in the construction and use of which the objects herein set out, as well as others, may be attained is illustrated in the accompanying drawings, in which—

Figure 1 is a front view of a comparator embodying my invention.

Figure 2 is a view in side elevation of the same with parts broken away to show construction.

In the accompanying drawings the numeral 5 denotes a base of the comparator which may be of any suitable form to support a column 6 rising from the base and having a recess 7 formed in one side and extending laterally therein. A shank 8 of a support 9 extends into the recess 7. Holding rods 10—11 extend in opposite directions from the top and bottom within bores in the column 6 that extend into the recess 7, the ends of such rods being engaged by ball bearings 12 located in recesses in the ends of the rods and in recesses in opposite sides of the shank 8, as shown in Fig. 2 of the drawings. The recess 7 is flared at its mouth so that the support 9 may be swung from side to side for a limited distance.

The support 9 is of U-shape, one arm 13 comprising an anvil for a die 14 which has a screw thread for engaging the thread of a separate member. The said die 14 has a groove 14a which separates the two rests 15, 15 of the die and thereby provides a two point support for the piece of work being gauged and prevents any foreign particles which would prevent accurate gauging from resting in the thread of the die 14. The other arm of the support comprises a head 16 in which is located a plunger 17 with a die 18 which conforms to the screw thread on the piece of work to be gauged and is formed opposite to that of the die 14 so that when the screw threaded piece rests in the die 14 on one side the opposite side of said thread will conform to and rest in the die 18. The plunger 17 with the die 18 thereon is pressed toward the die 14 as by means of a spring 19 confined within the head 16 by means of a cap 20. The die 18 is thus held pressed against a piece of work 21 being operated upon by the machine and a lever 22 is employed to move the die 18 away from the work piece to release the latter and free it for inspection.

2

It will be noted that when the piece of work 21 is being gauged between the dies 14 and 18 it is supported with a three point contact that is provided by the two portions 15, 15 and the die 18 and permits accurate gauging operation.

A dial indicator 23 is supported at the end of a rod 24 projecting from the top of the column 6, this indicator comprising a dial 25 for determining the condition of the work to be tested. A stem 26 for actuating the pointer within the indicator extends downwardly into contact with the plunger 17 which as hereinbefore stated is supported by the lever 22.

In the operation of the device the handle 27 of the lever 22 is pressed downward and this separates the dies 14—18 and the pointer of the compensator moves to an inactive position. During this operation the support 9 is swung laterally to one side, as shown in dotted outline in Fig. 1 of the drawings, as a convenient position for placing the work piece for operation upon it. This support may be retained in its normal position as shown in Fig. 2. In either instance it will be noted that the threaded piece to be tested may be presented to and engaged with the dies by moving the threads in the direction of extension of the threads so that the threads readily enter the grooves between the dies, and this ease of engagement of the threads of a work piece with the threads of the dies is a most important feature. Again the possibility of swinging the support to one side or the other is an important feature in the operation of the device owing to the facility with which the work pieces may be placed in position and then tested by release of the lever 22 to permit the stem 26 to allow operation of the pointer 28 to denote the condition of the threads of the work piece in a manner that will be readily understood.

40 I claim:

1. A comparator for testing the condition of threads on articles and including a jaw shaped support having rigid jaws forming an opening between them for the reception of the articles to be tested, dies formed to fit threads on said articles, at least one of said dies being movable in a jaw of said support, a sliding plunger associated with said movable die, gauge means operable by said plunger and aligned therewith for indicating 45 the distance between said dies and means for mounting the jaw-shaped support for horizontally swinging movements whereby the support may be laterally displaced relative to said gauge means for placement of an article therein to be tested.

2. A comparator for testing the condition of threads on articles and including a column rising from a base, a jaw shaped support with rigid jaws extending from said column, dies supported on opposite faces of said jaws and formed to fit the said threads, at least one of said dies being movable in said jaws, means for separating said dies for the reception of said articles, an indicator for indicating the distance between said dies, and means mounting said support on said column for movement about a vertical axis for the swinging of said support from side to side relatively to said indicator.

3. A comparator for testing the condition of threads on articles and including a vertical column rising from a base and having a recess in the side thereof, a jaw shaped support having rigid jaws with dies therein and having a shank extending into said recess, longitudinally extending rods in said column and engaging said shank from opposite sides thereof to provide a vertical pivot and retain the support in position, an indicator on the column above the jaw-shaped support and said support being pivotally movable in a horizontal plane out of line with the indicator for reception of an article to be gauged.

4. A comparator of the character described comprising a vertical column having a horizontal opening therein and axial bores extending through said column at opposite sides of said opening, a gauge comprising jaw shaped support having rigid jaws with dies therein and a shank fitting within said opening, a rod in each of said bores, a ball between the ends of each of said rods and shank, threaded means for adjustably positioning said rods to retain said balls in contact with said shank to permit horizontal pivotal movement thereof within said opening, and an indicator on the column above the gauge and operable by said gauge for indicating the distance between said dies.

5. A comparator for testing the condition of threads on articles and including a column rising from a base and having a recess in one side thereof, a jaw-shaped support having rigid jaws and a shank extending into said recess and pivotally mounted therein for horizontally swinging movements, a pair of dies oppositely supported in said jaws, one of said dies being movable in a jaw relative to the opposite die, spring means including a sliding plunger urging said movable die in the direction of the opposite jaw, means for moving the movable jaw and plunger in opposition to said spring means and an indicator on the column above the jaw shaped support and including a sliding plunger adapted to be engaged by the plunger of said spring means for indicating the distance between said jaws.

6. A comparator for testing the condition of threads on articles comprising a base, a column carried by said base, a support positioned transversely of said column and mounted on said column for swinging movement about a vertical axis, a pair of rigid jaws spaced vertically from each other on said support, coacting dies formed to fit threads on said articles interposed between said jaws, one of said dies being fixedly supported in one of said jaws and the other of said dies being mounted in the other of said jaws for movement toward and away from said fixed die, and gauge means carried by said column engageable with said movable die and operable in response to the movement of said latter named die away from said fixed die for indicating the distance between said dies.

7. A comparator for testing the condition of threads on articles comprising a base, a column carried by said base, a support positioned transversely of said column and mounted on said column for swinging movement about a vertical axis, a pair of rigid jaws spaced vertically from each other on said support, coacting dies formed to fit threads on said articles interposed between said jaws, one of said dies being fixedly supported in one of said jaws and the other of said dies being mounted in the other of said jaws for movement toward and away from said fixed die, gauge means carried by said column engageable with said movable die and operable in response to the movement of said latter named die away from said fixed die for indicating the distance between said dies, and spring means operatively connected to said movable die for urging the latter die toward said fixed die.

8. A comparator for testing the condition of threads on articles comprising a base, a column carried by said base, a support positioned transversely of said column and mounted on said column for swinging movement about a vertical axis, a pair of rigid jaws spaced vertically from each other on said support, coacting dies formed to fit threads on said articles interposed between said jaws, one of said dies being fixedly supported in one of said jaws and the other of said dies being mounted in the other of said jaws for movement toward and away from said fixed die, gauge means carried by said column engageable with said movable die and operable in response to the movement of said latter named die away from said fixed die for indicating the distance between said dies, spring means operatively connected to said movable die for urging the latter die toward said fixed die, and hand actuatable means exteriorly of said jaws and operatively connected to said movable die for moving the latter die against the tension of said spring means away from said fixed die.
